UNITED STATES PATENT OFFICE.

ALFRED COPONY, OF MOUNT CLEMENS, MICHIGAN.

METER BILL.

Application filed November 12, 1923. Serial No. 674,297.

To all whom it may concern:

Be it known that I, ALFRED COPONY, a citizen of the United States of America, residing at Mount Clemens, in the county of Macomb and State of Michigan, have invented 5 certain new and useful Improvements in Meter Bills, of which the following is a specification, reference being had therein to the accompanying drawings.

10 This invention relates to printed matter and refers more particularly to form sheets and the like that are designed for use by companies dealing in commodities that are measured by meters located on the customer's premises.

An object of the invention is to provide a form sheet that is adapted to be used by a meter reader of the company for rendering a bill directly to the customer at the time 20 the meter is read so that the clerical work and expense incident to the usual method of entering the meter reading at the main office and subsequent delivery of the bill to the customer is obviated.

25 Another object is to provide a form sheet that preferably consists of several sections which may be arranged so that the amount of money due the company, both with and without discount, and the discount date may 30 be recorded automatically when the meter reader designates the amount of the commodity used and the date of the meter reading.

Another object is to provide a form sheet 35 having places on one section that may be punched or marked by the meter reader by designating automatically on the other sections the house rating, an error or overcharge and that the bill covers a period of 40 two months because the meter was inaccessible the preceding month.

Another object is to provide a form sheet having sections which may be passed through suitable sorting machines after being received by the main office of the company for ascertaining the total amount of the commodity used by all its customers, the total amount of money in payment therefor, etc.

50 With the above and other objects in view, the invention consists of certain novel features of construction, combination and arrangement of parts as will be more fully de-

scribed and particularly pointed out in the appended claims.

55 In the accompanying drawings;

Figure 1 is a plan view of a form sheet embodying my invention;

Figure 2 is a view thereof when folded;

Figure 3 is a sectional view of the folded 60 form sheet;

Figure 4 is a plan view of a slightly modified form;

Figures 5 and 6 are plan views of another 65 modification;

Figure 7 is a plan view of a third modification.

Referring now to the drawings in which like characters of reference designate corresponding parts throughout the several views, 70 the numeral 1 designates a sheet that is preferably divided by spaced lines 2 and 3 respectively into three sections 4, 5 and 6 respectively.

The section 4 is preferably provided at 75 the upper left hand corner with a space 7 in which is preferably printed the words "Inspector's Check", the name of the company, and numerals representing the current year, while at the upper right hand 80 corner is a space 8 for the customer's name and address. Between the spaces 7 and 8 is a space 9 that is suitably lined and marked for recording the successive meter readings and the difference between the same, the latter representing the quantity of the commodity consumed. Located below the spaces 85 7, 8 and 9 respectively is a table 10 that is preferably printed on the section 4 and that 90 preferably represents kilowatt hours. The numbers in the table are preferably arranged in small spaces 11 that are formed by intersecting lines 12.

To the right of the table is a calendar 13 95 having numerals in multiples of five representing days of several months. These numerals are printed in small spaces 14 formed by intersecting lines 15. The spaces 14 are preferably arranged in rows that are spaced apart to provide small areas 16 in which the names of the months are printed. The name of each month in the calendar is 100 preferably printed twice, once below four numerals representing days of that month and again below two numerals representing 105 the remaining days of that month. The first

two numerals "25" and "30" in the top row 17 of the calendar represent days in the month of August, while the remaining numerals "5", "10", "15" and "20", respectively 5 represent days in the month of September.

The section 5 is preferably provided at the lower left hand corner with a space 18 in which is preferably printed the word "Voucher", the name of the company and 10 numerals representing the current year. To the right of this space are two spaces 19 and 20 respectively which correspond to the spaces 9 and 8 on the section 4. Above the spaces 18, 19 and 20 is a table 21 containing 15 numerals representing amounts in money. These numerals are preferably located in small spaces 22 formed by intersecting lines 23 that are arranged to register with the intersecting lines 12 on the section 4. As 20 it is customary for the company to allow a discount for payments made within a prescribed time, I preferably divide the spaces 22 by printed lines 24. The numerals in the spaces 25 above the lines 24 represent 25 the gross price to be paid, while the numerals in the spaces 26 below the lines 24 represent the net amount, the latter being preferably a ten per cent reduction of the gross price. Suitable instructions are preferably printed above the table 21, while at 30 the right of the table is a calendar 27 containing numerals in multiples of fives representing days of several months. These numerals are preferably arranged in spaced 35 rows 28 with the names of the months immediately above the same. The words "Discount date" are preferably printed above the calendar to indicate the numerals representing the limit date for payment of the net 40 price.

The section 6 is adapted to be folded on top of the section 5 and is provided at the upper left hand corner with a space 29 in which is printed the words "Customer's 45 bill", the name of the company, and numerals representing the current year. In the upper right hand corner of this section is a space 30 in which is printed the following:

50 *Base prices.*

House rating in K. W. H. or less, 12¢ P. K. W. H., net price is gross; balance, 4¢ P. K. W. H., price less 10%; minimum charge 50¢ gross, 45¢ net.

55 A table 31 and a calendar 32 are printed on the section 6 below the spaces 29 and 30 and contain the same indications as the table 21 and calendar 27 respectively. However, 60 this printing is in reverse order so that when the section 6 is folded the printing thereon will register with the printing on the section 5.

65 The tables 21 and 31 and the calendars 27 and 32 are preferably spaced the same distance from the line 3, while the tables 10

and 21 and the calendars 13 and 27 are preferably spaced the same distance from the line 2, consequently, proper registration of the printing on the sections when folded is assured.

In use, the meter reader of the company punches the folded sections of the sheet to indicate simultaneously the proper amount, dates, etc., on each section. In order that none of the printing on the three sections 70 will be destroyed by the punching, I preferably provide a series of circles 33 that are printed on the section 4 at one end of the spaces 11 containing the numerals of the table 10 and that indicate the points to be 75 punched. It will also be observed that the numerals of the tables 21 and 31 are preferably printed at the left end of the spaces so that the opposite end thereof will be 80 left blank to receive the punch holes.

85 Located at the right of the calendar 13 on the section 4 is a space 34 that is preferably divided by printed lines 35 into small areas in which is preferably printed "Punch here and date when meter is inaccessible" and a circle 34' indicating the point to be 90 punched; "Punch excess bill here"; and a circle 35' indicating the point to be punched, "Punch here"; and a mark 36' indicating the 95 point to be punched. At the top of this area is a small area 36 in which may be written the amount of money due the company when an error has been made on the stub or whenever the numbers in the table 10 are 100 inadequate to record the total amount of the commodity consumed by the customer.

The section 5 is provided with a space 37 which is also located at the right of the calendar 27 and which is divided by printed lines 38 into small areas into which is printed, "2 month bills are punched here"; "When punched here pay amount below"; and "House rating". This last area is preferably divided below the sheet by printed lines 39 into small spaces into which is printed the numerals 18, 15, 12 and 9 respectively, while at the lower end of the space 37 is a small area 40 corresponding to the area 36 on the section 4.

115 The section 6 is also provided with a space 41 that is located at the right of the calendar 32 and that is provided with printing corresponding to the printing in the space 37 on the section 5 except that it is in reverse order. Thus, when the sections are folded the printed matter in the spaces 41, 37 and 34 will register.

120 It is customary for companies dealing in commodities that are measured by meters to decide upon what is termed "a house rating" for the premises of its customers. This rating is usually determined by the company when the meter is installed and is used by the company in computing all bills rendered to the customer. With the form sheet illus-

trated in Figure 1, the house rating is 12, and has been designated on the inspector's check by a printed spot 42 that fills the circle in the space in which the numeral 12 of this table is printed. In order that the house rating designated as 12 in the table on the inspector's check will be designated on the voucher and customer's bill, the circle 36' is located at a particular point in the space 34 so that when the folded sections are punched, punch holes will be made in the spaces in which the number 12 is printed opposite to the words "House rating" on the sections 5 and 6 respectively.

The company preferably fills in the name and address of the customer and the last meter reading before the form sheet is handed to the inspector so that when the meter is read the inspector writes the present meter reading in the space 9 on the inspector's check and subtracts the last reading therefrom to obtain the amount of the commodity consumed by the customer for that month. The inspector then folds the sections and punches the circle 33 opposite to the figure in the table 10 corresponding to the amount of the commodity consumed so that the amount of money due the company will be designated by punch holes in the tables 21 and 31 respectively on the sections 5 and 6. The inspector also punches the mark 36' so that the proper house rating will be designated on the sections 5 and 6 and punches the proper numeral in the calendar 13 so that the date of the meter reading will be properly recorded on the inspector's check and so that the discount date will be recorded in the calendar 27 and 32 respectively on the sections 5 and 6. The inspector retains the section 4 and hands the sections 5 and 6 to the customer. The section 6 is preferably retained by the customer for future reference, while the section 5 is forwarded with the proper remittance to the company.

If the meter was inaccessible when the inspector called the preceding month at the customer's premises, the circle 34' on the section 4 is punched by the meter reader to designate on the sections 5 and 6 that the present bill covers a period of two months. Such a bill is made by the meter reader at the second visit who records in the space 9 on the inspector's check the total amount of the commodity consumed for the two months and punches the circle 33 opposite to the numerals which indicate the total amount of the commodity consumed. This punching records on the sections 5 and 6 the proper amount of money to be paid to the company. If desired this amount may be written in the areas 36, 40 and 43 respectively on the sections 4, 5, and 6. The meter reader also punches the proper numeral in the calendar 13 on the inspector's check to designate the date of the meter reading. This punching

will also simultaneously designate the proper discount date on the voucher 5 and customer's bill 6. In addition, the meter reader punches the circle 36' on the section 4 so that the proper house rating will be designated on the sections 5 and 6. 70

Whenever an error is made by the meter reader on the sheet or when the numbers in the tables 10 are inadequate to record the total amount of the commodity consumed by the customer, the circle 35' on the inspector's check 4 is punched by the meter reader to indicate that the customer should pay the amount of money that is written in the areas 40 and 43 respectively on the voucher and customer's bill. This amount is also written in the area 36 on the inspector's check for use by the company. 75

In the modification illustrated in Figure 4 the form sheet 50 is preferably provided with an inspector's check 51, a voucher 52 and a customer's bill 53 corresponding respectively to the section 4, voucher 5 and bill 6 illustrated in Figure 1. The sheet 50 is also provided with a fourth section 54 that is connected to the lower edge of the customer's bill 53 and that corresponds to the voucher 52. This voucher 54 is adapted to be folded below the customer's bill 53 so that it will be punched simultaneously with the other sections of the sheet. The voucher 54 together with the inspector's check 51 are retained by the meter reader for use by the company, while the voucher 52 and customer's bill 53 are handed by the meter reader to the customer at the time the meter is read. Thus, should the customer lose or misplace the voucher 52 and bill 53 the company will have a complete record thereof at their offices. 80

In the modification illustrated in Figures 5 and 6, I have shown a form sheet that is provided on one face thereof with an inspector's check 60, a voucher 61 and a customer's bill 62 corresponding to the section 4, voucher 5 and bill 6 of the form sheet illustrated in Figure 1 and that is also provided on the rear face thereof with a voucher 63 containing the same indications as the voucher 61. However, the printing on the voucher 63 is in reverse order to the printing on the voucher 61 and is preferably arranged on the rear face of the inspector's check 60 so that when the latter is punched a duplicate of the bill handed to the customer will be made for use by the company. 90

In Figure 7 I have shown a form sheet 70 that corresponds to the form sheet 1 except that the numerals in the table 71 on the inspector's check 72 thereof are arranged differently. As shown in Figure 7, the house rating is designated on the inspector's check by a black spot 74 that fills the circle opposite to "18" in the table 71, consequently, the circle 75 on the inspector's check indi- 100

cating the point to be punched for designating the house rating 18 on the voucher 76 and the customer's bill 77 respectively, is located at a lower point. Thus, when the 5 sections of the sheet are folded in superposed relation and the number "152" in the table 71 is punched, the amount of money due the company designated on the sections 76 and 77 will include the proper 10 amount of money for the house rating in kilowatt hours at 12 cents per kilowatt hour. For example, the gross charge, \$7.52 for 152 units, includes \$2.16 to cover the house rating "18" at 12 cents per kilowatt hour 15 and \$5.36 to cover the balance 134 to 4 cents per kilowatt hour.

With the form sheets described, the company may readily obtain the total amount 20 of the commodity consumed by all its customers by merely passing the separate sections of the form sheets through a suitable sorting machine. For instance, the inspector's checks could be passed through a machine having means for engaging the punch 25 holes therein to sort the checks according to the indications designated such as the house rating, the amount of commodity used, etc. Likewise, the vouchers could be sorted to obtain the total amount of money due or 30 received by the company.

What I claim as my invention is:

1. A form sheet of the class described comprising a series of sections adapted to be folded in superposed relation, each section 35 having a table thereon, said sections being adapted to be punched when folded to designate certain numerals in each of said tables, and means on one section for indicating points thereof to be punched whereby the punch holes formed in the other sections 40 will be spaced from the numerals designated.

2. A form sheet of the class described comprising a series of sections adapted to be folded in superposed relation, each section 45 having suitable indicia thereon for designating the amount of commodity consumed and the amount of money due the company therefor, said sections being adapted to be punched when folded for designating simultaneously the proper indicia on all 50 sections and one of said sections having punch hole locations accurately indicated thereon, whereby when said sections are separated the punch holes therein may be engaged by mechanical means for classifying said sections.

3. A form sheet of the class described comprising a series of sections adapted to be folded in superposed relation, one section 60 having suitable indicia for indicating the amount of the commodity consumed and the date of the meter reading, and the other sections having suitable indica for indicating the amount of money due the company 65 for the commodity consumed and the dis-

count date, and adapted to be simultaneously designated when the amount of the commodity consumed and the date of the meter reading is designated.

4. A form sheet of the class described 70 comprising a series of sections adapted to be folded in superposed relation, one section having a table representing amounts of the commodity consumed, the other sections having tables representing amounts of money 75 due the company for the commodity consumed, said sections being adapted to be punched for indicating the proper amounts in said tables, and means on said sections for registering amounts exceeding the tables. 80

5. A form sheet of the class described comprising a series of sections adapted to be folded in superposed relation, one section having suitable indicia representing amounts 85 of the commodity consumed, the other sections having suitable indicia representing amounts of money due the company for the commodity consumed, means on one section for registering the inaccessibility of the meter, and means on the other sections 90 for designating a two months' bill when the inaccessibility of the meter is designated.

6. A form sheet of the class described 95 comprising a series of sections adapted to be folded in superposed relation, each section having suitable indicia thereon for designating the amount of commodity consumed and the amount of money due the company therefor, said sections being adapted to be punched when folded for designating simultaneously the proper indicia on all sections, and means for designating on one section 100 the points to be punched so that indicia on none of the sections will be destroyed. 105

7. A form sheet of the class described comprising a plurality of sections adapted to be folded in superposed relation, one section having a table provided with quantity 110 indications, certain of said indications representing house ratings, means for designating a particular house rating on said section, the other section having cost indications and house rating indications, and means on the first section designating the point to be punched for indicating the proper house rating on the second section, the cost indications being arranged on the second section to register with the quantity indications on the first section when said sections are folded whereby punching of a particular quantity 115 will simultaneously punch the proper cost indication.

8. A form sheet of the class described 125 comprising a series of sections adapted to be folded in superposed relation, one section having quantity indications thereon and means for designating a house rating, the other sections having cost indications and house rating indications thereon, said sec- 130

- tions being adapted to be punched by the meter reader when folded to designate certain of the indications thereon, and means on one section for designating the point to be punched for designating the proper house rating on the other section, the cost indication being arranged to register with said quantity indications whereby punching of a particular quantity on one section will designate by punch holes the proper cost indications on the other sections. 10
- 5

In testimony whereof I affix my signature.

ALFRED COPONY.
